UNITED STATES PATENT OFFICE

ALBERT B. DICK, OF LAKE FOREST, ILLINOIS, ASSIGNOR TO A. B. DICK COMPANY, OF CHICAGO, ILLINOIS, A CORPORATION OF ILLINOIS.

STENCIL-DUPLICATING APPARATUS.

No. 922,862.

Specification of Letters Patent.

Patented May 25, 1909.

Application filed February 19, 1909. Serial No. 478,854.

To all whom it may concern:

Be it known that I, ALBERT B. DICK, a citizen of the United States, residing at Lake Forest, in the county of Lake and State of Illinois, have invented certain new and useful Improvements in Stencil-Duplicating Apparatus, (Case A,) of which the following is a specification.

This invention relates particularly to that type of duplicating apparatus in which is employed a stencil-carrying drum or segment of a drum to which rotary or oscillatory movement is transmitted by suitable means and upon the surface of which is secured a stencil-sheet through which characters are imprinted upon an impression-sheet passing between the periphery of such drum or segment and an underlying pressure device, as, for instance, a roller.

The invention also relates particularly to means for applying to duplicating apparatus of this general class the ink which is passed through the interstices in the stencil-sheet for the purpose of imprinting upon the impression-sheets.

Heretofore it has been the practice in both rotary and oscillatory duplicators to provide the drum with a foraminated metallic stencil-carrier, over which is stretched a pad of flannel or similar material, on the exterior of which the stencil is adjusted. The ink has commonly been applied by means of a hand-brush, and this, besides being attended by some difficulty and inconvenience, particularly in machines wherein the entire surface of the drum has been covered by the foraminated stencil-carrier, has proved objectionable as lacking neatness, being wasteful of ink, and permitting the application of such ink to parts where it either could not be utilized or for which it was not intended.

Under the present invention, I make the inking apparatus of a duplicating machine practically a part of that machine, either as to the container for the ink alone, or as to the distributor for such ink alone, or as to both. In a preferred form of the invention, the drum is provided with an ink-container which may either be part of the permanent structure of the machine or adapted to receive ink in a can as put up at the factory. Suitable means are provided for permitting the flow of ink from such can or container to the interior of the drum, and a distributing device is employed, preferably manually, op-

erated, whereby the ink so deposited may be brushed or otherwise distributed over the interior of the drum either throughout the entire area thereof or at particular parts, as may be desired.

The invention is illustrated in the accompanying drawings, in which—

Figure 1 is a side elevation of a stencil-duplicating machine provided with my improvements; Fig. 2 is a central longitudinal section thereof; Fig. 3 is a transverse section, certain of the parts being shown in elevation; Fig. 4 is an end view of the ink-containing and -distributing apparatus; Fig. 5 is a transverse section, and Fig. 6 a longitudinal section, of a portion of the duplicator drum equipped with an ink-container of modified form; Fig. 7 is an end view of ink-containing and -distributing apparatus constituting a modification of the corresponding apparatus shown in Fig. 4; Figs. 8, 10 and 11 are detail views hereinafter to be referred to; and Fig. 9 is a transverse section, partly in elevation, of a simplified form of the apparatus, showing an ink-distributing apparatus, without, however, the ink-containing device or devices illustrated in the other figures.

Referring to these drawings, it will be seen that the stencil-carrying drum comprises the heads A, the foraminated stencil-carrier A', and the ink-pad A'', over which is secured by any suitable means, as, for instance, the cross-bar A''' and clamp A''', the stencil-sheet in which the characters have previously been formed. This drum is pivotally mounted in the upwardly-extending arms of the frame B, and coacting with the periphery thereof is a pressure-roller B' mounted in hinged spring-pressed arms B'' with which coacts throw-off mechanism comprising shaft B'', eccentrics B'', and finger-piece B''. The drum is rotated by means of crank-handle C mounted upon a stub-shaft C' journaled in the frame and transmitting motion to the pinions C'' and C'''.

Referring now more particularly to the inking apparatus, attention is first called to the simplified form in which this is illustrated in Fig. 9. Here, in addition to the shaft upon which the drum is mounted, there is a telescope-shaft a to one end of which is secured the crank-handle a', the other end of said telescope-shaft a, within the drum, being provided with a sleeve a'', to which is adjustably secured an ink-distributer a'''. In this

form of apparatus, the ink is designed to be 5 poured or otherwise deposited, from a suitable can or other container, into or upon the interior of the stencil-carrier, after which it is spread by means of the distributer a^3 manually operated by means of the crank-handle a' . It will also be seen that the ink may be spread over the entire area of the stencil-carrier or over only such parts thereof 10 as may be desired, this being entirely within the control of the operator. In the more comprehensive form in which the invention has been embodied, the ink is carried within the drum, as above indicated and as illustrated in the other figures, which will now be 15 described.

Referring more particularly to Fig. 3, it will be seen that the drum is mounted, at its rearward end, upon a hollow stub-shaft b 20 carried by one of the upwardly-extending arms of the frame. The other end of the drum is mounted upon a similar hollow stub-shaft b' carried, at b^2 , by the other of the upwardly-extending arms of the frame. Keyed 25 to a collar upon said stub-shaft is the pinion C^3 provided on its inner face with a pin (shown in dotted lines in Fig. 1) coacting with an orifice in the adjacent head of the drum, so that upon the application of power 30 to said pinion through pinion C^2 and crank-arm C , rotary motion will be transmitted to the drum. The stub-shaft b' is also provided with an enlarged head b^3 for coaction with the brake c^4 operated by the finger-piece B^5 of the 35 throw-off mechanism.

D designates the inking-rod. This extends through the hollow stub-shaft b' , its rearward end being received in the hollow stub-shaft b . This rod is operated by means of the crank- 40 handle D' extending at a right angle thereto and secured to the angular piece d forming one of two braking members, the other being the shoe d' of the brake c^4 . Said shoe is provided with a pin d^2 which coacts with an orifice d^3 in said angular piece. In Fig. 1, the 45 parts are illustrated in the position which they occupy when the pressure-roller B' is inoperative. Since it is under this condition that a duplicator is commonly inked, the locking device just described is inoperative, *i. e.*, the crank-handle D' is free to be moved as hereinafter described. When, however, the finger-piece B^5 of the throw-off mechanism is thrown to its alternative position, 50 opposite to the position in which it is shown in Fig. 1, the brake-shoe under the influence of the spring d^4 is thrown to inoperative position, and the coaction of the pin d^2 with the orifice d^3 locks the crank-handle D' in the position in which it is illustrated in said figure. 55

Loosely mounted upon the inking-rod D , are two yokes D^2 , D^3 , the ends of which are connected by guide-rods D^4 , D^5 . Mounted so as to slide upon said guide-rods, is the ink- 60 containing and -distributing apparatus, two

forms of which are illustrated in the drawings. In the form illustrated chiefly in Figs. 2, 3 and 4, I employ an ink-container E mounted, as best shown in Fig. 2, upon the guide-rods D^4 , D^5 , and through which projects the inking-rod D . In the forward side e of the container is formed an oblique slot e' , within which operates a lock for the inking-rod D . Said rod is provided, as best shown in Figs. 3, 8, 10 and 11, with a reduced portion F , and this portion is provided with a notch so formed that the cross-sectional outline through such reduced portion is substantially semicircular. The lock G , provided with the finger-piece g , is received 70 snugly within the slot e' , its lower end coacting with a coil-spring g' in said slot (see Fig. 8) tending to press the lock upwardly. The slot e' , and therefore the lock G , lie in the path of longitudinal movement of the inking-rod D , as best shown in Figs. 2 and 8. Said lock is provided, therefore, with a notch g^2 of 75 semicircular configuration. When the lock has been pressed inward against the tension of the coil-spring g' , so that this notch coincides with the opening through the side-plate e and therefore through the ink-container, the end of the inking-rod D may be passed into said container until movement is arrested by the coaction of the edge of the reduced portion F with said lock G . Upon further depressing said lock, so as to break this coaction, the end of the inking-rod may be passed entirely through the container and received within the hollow stub-shaft b , as 80 shown in Fig. 3. This is the normal condition of the mechanism, and that which it occupies when the pressure-roller is in operative position and the brake c^4 in inoperative position, at which time the crank-handle 85 lock (d^2 , d^3) is operative to hold said crank-handle against accidental displacement. 90

The container E is provided with a filling-port E' , which may be closed by a suitable screw-cap. The side-member e of said container is here shown as covered by a circular plate e^2 secured in position by suitable screws. This is provided with a slot e^3 open to the periphery of said plate e^2 , and in this slot operates the pin e^4 carried by the lock G , the function of which will presently be explained. Secured to the face-plate e^2 , is a hub e^5 having ears e^6 , e^6 . Mounted upon said hub is a combined valve and latch H , preferably formed of spring-metal and operated by the finger-piece h . The member H may be readily secured in position upon the hub e^5 , by first causing the notches adjacent to the perforation therein to register with the ears e^6 , e^6 , then pressing said member rearwardly 110 and turning it so that said notches and ears shall be out of engagement. Secured in any suitable manner to the inner face of the combined valve and latch, are stoppers h' , h^2 , the former, in the position illustrated in 115 120 125 130

Fig. 2, covering the air-inlet port communicating with the interior of the container E, and the latter, when in the position so illustrated, covering the ink-outlet port in said container. The movement of the member H to the left, Fig. 2, simultaneously uncovers both of said ports, permitting ink in the container to escape therefrom and to fall on the stencil-carrier. The latch function of the member H is performed by means of a right-angled slot h^3 , with which, as well as with the slot e^3 in the face-plate e^2 , the pin e^4 of the lock G coacts. In the normal position of the parts, in which they are illustrated in Fig. 2, the lock G is in its innermost position, and the end of the inking-rod distant from the crank-handle thereon is housed in the hollow stub-shaft b . If, now, said rod be unlocked at d^2 , d^3 , and moved outward from the drum (the ink-container being held against similar movement), the reduced portion F of said rod is brought into the path of movement of the lock, which is thereby moved upwardly by the spring g but not sufficiently to permit the pin e^4 to escape from the radial portion of the slot h^3 . At this time, the reduced portion F is in contact with the semicircular notch g^2 of said lock. If, now, the rod D be given a partial rotation; so as to present the semicircular notch therein to said lock G, the latter is permitted to rise to the position illustrated in Fig. 10, thereby, first, locking the rod and the container together so that the latter may be moved both longitudinally of the drum and circumferentially, and, second, permitting the pin e^4 to rise sufficiently far in the slot e^3 as to allow the valve-member H to be operated to uncover the air-inlet port above and the ink-outlet port below. When this has been done, the ink is permitted to drop, as above described. The slot-and-pin device also precludes the release of the rod to restore it to inoperative position while said ports are open, thus guarding against excessive flow of ink from the container E.

Preferably secured to the ink-container or to some part movable therewith, is an ink-distributer, which may take any desired form. In the present instance, I have illustrated, for the purpose of this particular disclosure, a brush I attached to a plate i adjustably secured to the rear face of the container E by screws i', projecting through slots in said plate i. In Fig. 7, substantially the same arrangement is shown, the design being somewhat varied, however; and a spring i'' being employed to exert elastic pressure upon the brush. Said brush may, in either construction, be adjusted, relatively to the stencil-carrier, to allow for wear, or may be lifted entirely free from the stencil-carrier and secured in such position, if desired.

In Figs. 5 and 6, I have illustrated a modification of the ink-containing device; the

purpose here being to disclose the manner in which, if desired, a permanent ink-container may be dispensed with; and, by means of a suitable cage or holder, an ink-can (as an "original package") containing ink placed therein to perform practically the same function as the permanent container heretofore described. In this modification, there are supported upon the guide-rods D⁴, D⁵, both the ink-distributer (in substantially the form heretofore described) and a cage or can-holder comprising a back-plate L provided with ears adapted to receive bolts l, l. In the particular device illustrated, it is contemplated that the cover of the can as applied in the factory shall be removed when it is desired to utilize the ink and a cover substituted therefor made with special view to the requirements of the duplicator, although this is not necessary in several forms in which the invention herein described may be employed. In the construction illustrated, the special cover is shown at M; this having an annular flange m corresponding to the flange of the usual ink-can cover, and a bearing m' for the inking-rod corresponding to the inking-rod D heretofore explained. In this case, the inking-rod is provided at its end with a notch adapted, when in its innermost position, to coact with the pin m² in said bearing. Said inking-rod is also provided with a recess m³ with which coacts a spring m⁴, in order that the can-holder and can carried thereby may be moved by the inking-rod both longitudinally of the drum and circumferentially. The auxiliary cover M is also provided with an ink-outlet port m⁵, opened and closed by means of valve m⁶. To secure the "original package" can in position, after having substituted the auxiliary cover for the regular cover thereof, it is only necessary to place the bottom of such can against the plate L and to secure it against displacement by means of the bolts l, l, which not only hold the can rigidly but also preclude the possibility of disarrangement of the auxiliary cover M and consequent leakage of ink.

The operation of the apparatus has been explained to considerable extent in connection with the description of the parts. Normally and when the inking apparatus is out of use, the parts occupy the position in which they are illustrated in Figs. 1, 2 and 3. When it is desired to apply ink to the stencil-carrier, either over its entire area or at certain portions thereof, the crank-handle D' is released from its lock (d², d³), the container E held and the rod drawn partially out from the drum and then given a partial rotation. As a result, by means of the locking device heretofore described, the end of the rod is rigidly attached to the ink-container, which, together with the distributer moving therewith, may now, by means of the

crank-handle, be moved to any desired point within the drum. The ink-outlet port is uncovered to permit the flow of sufficient ink, which is thus distributed over the stencil-carrier, and moreover, since the range of movement of the distributor is predetermined and limited to useful service of the carrier, the daubing of other parts with ink is precluded. After the ink-outlet port has been closed and sufficient ink has been distributed as above described, the lock G is pressed inward to its inoperative position, the rod similarly manipulated, and the crank-arm locked if desired. In the particular mechanism here shown and described, the throw-off mechanism (including hand-piece B⁵, eccentric B⁴ and shaft B³) is so arranged as that when the machine is in operative position for duplicating purposes, the crank-handle will be locked. When said mechanism is so arranged as that (by reason of the depression of the pressure-roller) the machine is inoperative for duplicating purposes, the brake c⁴ is in operative position and the crank-handle released from the lock d², d³, to permit the inking of the stencil-carrier as above described.

Having now described my invention, what I claim as new therein and desire to secure by Letters Patent is as follows:—

1. In duplicating apparatus, the combination with a stencil-carrying drum and means for supplying ink thereto, of an ink-distributer within said drum, and means for moving said distributor longitudinally and transversely in contact with the interior of said drum, substantially as set forth.

2. In duplicating apparatus, the combination with a stencil-carrying drum and means for supplying ink thereto, of an ink-distributer within said drum, and means controlled outside said drum for moving said distributor longitudinally and transversely of said drum in contact with the interior thereof, substantially as set forth.

3. In duplicating apparatus, the combination with a stencil-carrying drum, and means for supplying ink thereto, of a pivotally mounted ink-distributer within said drum, and means for moving said distributor longitudinally of said drum and in contact with the interior thereof, substantially as set forth.

4. In duplicating apparatus, the combination with a stencil-carrying drum, and means for supplying ink thereto, of a pivotally mounted ink-distributer within said drum, and means for oscillating said distributor transversely of said drum in contact with any desired portion of the interior thereof, substantially as set forth.

5. In duplicating apparatus, the combination with a stencil-carrying drum and means for supplying ink thereto, of a pivotally

mounted ink-distributer within said drum, and means for moving said distributer longitudinally and transversely of said drum and in contact with the interior thereof, substantially as set forth.

6. In duplicating apparatus, the combination with a stencil-carrying drum, and means for supplying ink thereto, of an ink-distributer within said drum, and means for bodily moving the same longitudinally and transversely of said drum and in parallelism with the interior thereof, substantially as set forth.

7. In duplicating apparatus, the combination with a stencil-carrying drum, and means for supplying ink thereto, of a spring-pressed ink-distributer within said drum, and means for bodily moving the same longitudinally and transversely of said drum and in parallelism with the interior thereof, substantially as set forth.

8. In duplicating apparatus, the combination with a stencil-carrying drum, and means for supplying ink thereto, of an ink-distributer within said drum, and means for moving said distributor relatively to said drum, said distributor, when in inoperative (non-distributing) position, moving bodily with said drum, substantially as set forth.

9. In duplicating apparatus, the combination with a stencil-carrying drum of foraminous material and a stencil detachably secured thereon, of means for supplying ink to the interior of said drum, and an ink-distributer mounted for oscillating movement within said drum and movable, when said drum is at rest, into contact with any desired portion of the interior of said drum, substantially as set forth.

10. In duplicating apparatus, the combination with a stencil-carrying drum, and means for supplying ink thereto, of an ink-distributer mounted within said drum and bodily movable both longitudinally and transversely thereof, substantially as set forth.

11. In duplicating apparatus, the combination with a stencil-carrying drum and means for supplying ink thereto, of an ink-distributer supported centrally of said drum, and means for oscillating the same in contact with any desired portion of the interior of said drum, substantially as set forth.

12. In duplicating apparatus, the combination with a stencil-carrying drum, and means for supplying ink thereto, of an ink-distributer supported centrally of said drum, and mechanism, controlled outside said drum for moving said distributor about its support and in contact with any desired portion of the interior of said drum, substantially as set forth.

13. In duplicating apparatus, the combination with a stencil-carrying drum, and

- means for supplying ink thereto, of an ink-distributer pivoted centrally of said drum and means for moving the same longitudinally and transversely therein, substantially as set forth. 5
14. In duplicating apparatus, the combination with a stencil-carrying drum, and means for supplying ink thereto, of an ink-distributer pivoted centrally of said drum, and means, controlled outside said drum, for moving said distributor longitudinally and transversely of said drum, substantially as set forth. 10
15. In duplicating apparatus, the combination with a stencil-carrying drum, and means for supplying ink thereto, of an ink-distributer pivoted centrally of said drum and means for moving the same longitudinally and transversely therein under the influence of mechanism controlled outside said drum, said distributor, when not in operation, occupying a fixed position with relation to said drum, substantially as set forth. 15
- 20 16. In duplicating apparatus, the combination with a stencil-carrying drum, of an ink-container mounted wholly within said drum and means for moving the same within said drum and longitudinally thereof, substantially as set forth. 25
- 30 17. In duplicating apparatus, the combination with a stencil-carrying drum, of an ink-container therein and means for moving the same longitudinally and transversely of said drum, substantially as set forth. 35
- 35 18. In duplicating apparatus, the combination with a stencil-carrying drum, of an ink-container centrally mounted therein and means for moving the same within said drum and longitudinally thereof, substantially as 40 set forth. 45
19. In duplicating apparatus, the combination with a stencil-carrying drum, of an ink-container centrally mounted therein and means for moving the same longitudinally and transversely of said drum, substantially as set forth. 50
20. In duplicating apparatus, the combination with a stencil-carrying drum, of an ink-container and -distributer mounted therein and means for moving the same independently in parallelism with the interior of said drum and both longitudinally and transversely thereof, substantially as set forth. 55
21. In duplicating apparatus, the combination with a stencil-carrying drum, of an ink-container and an ink-distributer secured thereto, and means for moving said distributor in parallelism with the interior of said drum and both longitudinally and transversely thereof, substantially as set forth. 60
22. In duplicating apparatus, the combination with a stencil-carrying drum, of an ink-container and -distributer mounted there- 65
- in, and means for bodily moving said distributor longitudinally and transversely of said drum, substantially as set forth. 70
23. In duplicating apparatus, the combination with a stencil-carrying drum, of an ink-container and an attached ink-distributer mounted therein, and means controlled outside said drum for moving said distributor in contact with any desired portion of the interior of said drum, substantially as set forth. 75
24. In duplicating apparatus, the combination with a stencil-carrying drum, of an ink-container and an attached ink-distributer mounted therein, and means controlled outside said drum for moving said container and distributor the latter in contact with any desired portion of the interior of said drum, substantially as set forth. 80
25. In duplicating apparatus, the combination with a stencil-carrying drum, of an ink-container and -distributer mounted therein and adjustable relatively to each other, substantially as set forth. 85
26. In duplicating apparatus, the combination with a stencil-carrying drum, and means for supplying ink thereto, of an ink-distributer within said drum and adjustable relatively to the interior thereof, substantially as set forth. 90
27. In duplicating apparatus, the combination with a stencil-carrying drum, of an ink-container and -distributer mounted therein, said distributor being movable in parallelism with the interior of said drum and adjustable relatively thereto, substantially as 95 set forth. 100
28. In duplicating apparatus, the combination with a stencil-carrying drum, and means for supplying ink thereto, of an ink-distributer within said drum, means for manually oscillating said distributor in contact with any desired portion of the interior of said drum, and a lock for said distributor, substantially as set forth. 105
29. In duplicating apparatus, the combination with a stencil-carrying drum, of an ink-container and an attached ink-distributer mounted therein and movable in parallelism with the interior of said drum, and a lock for said container and distributer 110 operating to hold the same in fixed, inoperative position relatively to said drum, substantially as set forth. 115
30. In duplicating apparatus, the combination with a stencil-carrying drum, and means for supplying ink thereto, of an ink-distributer within said drum, and a rod for moving said distributor within said drum and in contact with any desired portion thereof, substantially as set forth. 120
31. In duplicating apparatus, the combination with a stencil-carrying drum, and means for supplying ink thereto, of an ink- 125

distributer within said drum, a rod for moving said distributer within said drum and in contact with any desired portion thereof, and a lock for said distributer, substantially as set forth.

32. In duplicating apparatus, the combination with a stencil-carrying drum, and means for supplying ink thereto, of an ink-distributer within said drum, and a rod for moving said distributer within said drum, said rod being movable longitudinally of said drum, substantially as set forth.

33. In duplicating apparatus, the combination with a stencil-carrying drum, and means for supplying ink thereto, of an ink-distributer within said drum, and a rod for moving said distributer within said drum and in contact with any desired portion of the interior thereof, said rod being capable of rotary motion, substantially as set forth.

34. In duplicating apparatus, the combination with a stencil-carrying drum, and means for supplying ink thereto, of an ink-distributer within said drum, and a rod for moving said distributer within said drum, said rod being movable longitudinally of said drum and being capable also of rotary motion, substantially as set forth.

35. In duplicating apparatus, the combination with a stencil-carrying drum, of an ink-container therein, and a rod for moving said container within and longitudinally of said drum, substantially as set forth.

36. In duplicating apparatus, the combination with a stencil-carrying drum, of an ink-container therein, a rod for moving said container within and longitudinally of said drum, and a lock for said container operating to hold the same in fixed position relatively to said drum, substantially as set forth.

37. In duplicating apparatus, the combination with a stencil-carrying drum, of an ink-container and -distributer mounted therein, and a rod for moving said distributer into contact with any desired portion of the interior of said drum, said rod being capable of rotary motion, substantially as set forth.

38. In duplicating apparatus, the combination with a stencil-carrying drum, of an ink-container and -distributer mounted therein, and a rod for operating the same, said rod being capable of longitudinal motion, substantially as set forth.

39. In duplicating apparatus, the combination with a stencil-carrying drum, of an ink-container and -distributer mounted therein, and a rod for operating the same, said rod being capable of rotary and longitudinal motion, substantially as set forth.

40. In duplicating apparatus, the combination with a stencil-carrying drum, and means for supplying ink thereto, of an ink-distributer within said drum, a rod for moving said distributer longitudinally and transversely within said drum, and a lock coöperating with said distributer and said rod, substantially as set forth.

erating with said distributer and said rod, substantially as set forth.

41. In duplicating apparatus, the combination with a stencil-carrying drum, of an ink-container therein, a rod for moving said container longitudinally within said drum, and a lock coöperating with said container and said rod, substantially as set forth.

42. In duplicating apparatus, the combination with a stencil-carrying drum, of an ink-container and -distributer mounted therein, a rod for moving said container and distributer longitudinally and transversely within said drum, and a lock coöperating with said container and distributer and with said rod, substantially as set forth.

43. In duplicating apparatus, the combination with a stencil-carrying drum, and means for supplying ink thereto, of a brush within said drum, and means for manually moving said brush in contact with any portion of the interior of said drum while said drum is at rest, substantially as set forth.

44. In duplicating apparatus, the combination with a stencil-carrying drum and means for supplying ink thereto, of a brush within said drum, and a rod for moving said brush into contact with any portion of the interior of said drum while said drum is at rest, substantially as set forth.

45. In duplicating apparatus, the combination with a stencil-carrying drum, and means for supplying ink thereto, of a brush within said drum, and a manually operated rod for moving said brush longitudinally of said drum, substantially as set forth.

46. In duplicating apparatus, the combination with a stencil-carrying drum, and means for supplying ink thereto, of a brush within said drum, and a rod for bodily moving said brush transversely of said drum, substantially as set forth.

47. In duplicating apparatus, the combination with a stencil-carrying drum, and means for supplying ink thereto, of a brush within said drum, and a rod for moving said brush longitudinally and transversely of said drum, substantially as set forth.

48. In duplicating apparatus, the combination with a stencil-carrying drum, of an ink-container and brush mounted therein, said brush being movable longitudinally and transversely of said drum, substantially as set forth.

49. In duplicating apparatus, the combination with a stencil-carrying drum, of an ink-container and -distributer mounted therein, a rod movable longitudinally of said drum, a lock coöperating with said container and distributer and with said rod, and a valve for said container coöperating with said lock, substantially as set forth.

50. In duplicating apparatus, the combination with a stencil-carrying drum, of a guide device within said drum, and a longi-

- tudinally movable ink-container mounted upon said guide device, substantially as set forth.
51. In duplicating apparatus, the combination with a stencil-carrying drum, of a guide device centrally positioned within said drum, and a container and distributer movably mounted upon said guide device, substantially as set forth.
52. In duplicating apparatus, the combination with a stencil-carrying drum, of a guide device centrally positioned within said drum, and a container and brush movably mounted upon said guide device, substantially as set forth.
53. In duplicating apparatus, the combination with a stencil-carrying drum, of a pivotally mounted frame therein, and an ink container carried by said frame and having ink-inlet and outlet ports, substantially as set forth.
54. In duplicating apparatus, the combination with a stencil-carrying drum, of a pivotally mounted frame therein, and an ink container carried by said frame and movable relatively thereto said container having ink-inlet and outlet ports, substantially as set forth.
55. In duplicating apparatus, the combination with a stencil-carrying drum, of a pivotally mounted frame therein, and an ink container and distributer carried by said frame, substantially as set forth.
56. In duplicating apparatus, the combination with a stencil-carrying drum, of a pivotally mounted frame therein, and an ink container and distributer carried by said frame and movable relatively thereto, substantially as set forth.
57. In duplicating apparatus, the combination with a stencil-carrying drum, of a pivotally mounted frame therein, an ink container and distributer carried by said frame and movable relatively thereto, and an operating rod for said container and distributer, substantially as set forth.
58. In duplicating apparatus, the combination with a stencil-carrying drum, of a cage or holder, an ink-container detachably supported therein and means for moving said cage or holder relatively to said drum, substantially as set forth.
59. In duplicating apparatus, the combination with a stencil-carrying drum, of means for detachably supporting an ink-container and -distributer therein and for moving the same relatively to said drum, substantially as set forth.
60. In duplicating apparatus, the combination with a stencil-carrying drum, of an ink-container within said drum and provided with a valve, means for moving said container, and mechanism for precluding such movement save when such valve is closed, substantially as set forth.
61. In duplicating apparatus, the combination with a stencil-carrying drum, of a frame pivotally mounted therein, an ink-container and -distributer carried by said frame, and a rod, operable from outside said drum, for moving said container and distributer, substantially as set forth. 65
62. In duplicating apparatus, the combination with a stencil-carrying drum, of a frame pivotally mounted therein, an ink-container and -distributer carried by said frame, and a rod, operable from outside said drum, for moving said container and distributer, said rod having a detachable connection with said container and distributer, substantially as set forth. 70
63. In duplicating apparatus, the combination with a stencil-carrying drum, of an ink-container within said drum and provided with a valve, an operating rod for said container, and locking mechanism coöperating with said rod and valve, substantially as set forth. 75
64. In duplicating apparatus, the combination with a stencil-carrying drum, of an ink-container within said drum and provided with a valve and distributer, an operating rod for said container, and locking mechanism coöperating with said rod and valve, substantially as set forth. 80
65. In duplicating apparatus, the combination with a stencil-carrying drum, of an ink-container within said drum, and movable longitudinally thereof, its major axis being arranged transversely of said drum, substantially as set forth. 85
66. In duplicating apparatus, the combination with a stencil-carrying drum, of an ink-distributer within said drum and movable longitudinally thereof, its major axis being arranged transversely of said drum, substantially as set forth. 90
67. In duplicating apparatus, the combination with a stencil-carrying drum, of an ink-container and -distributer within said drum and movable longitudinally thereof, their major axes being arranged transversely of said drum, substantially as set forth. 95
68. In duplicating apparatus, the combination with a stencil-carrying drum and means for supplying ink thereto, of an ink-distributer within said drum, and means controlled outside said drum for manually moving said distributer within said drum both longitudinally and transversely thereof, substantially as set forth. 100
69. In duplicating apparatus, the combination with a stencil-carrying drum, of an ink-container and -distributer within said drum and movable longitudinally thereof, their major axes being arranged transversely of said drum, substantially as set forth. 105
70. In duplicating apparatus, the combination with a stencil-carrying drum, of an ink-container and -distributer within said drum and movable longitudinally thereof, their major axes being arranged transversely of said drum, substantially as set forth. 110
71. In duplicating apparatus, the combination with a stencil-carrying drum, of an ink-container and -distributer within said drum and movable longitudinally thereof, their major axes being arranged transversely of said drum, substantially as set forth. 115
72. In duplicating apparatus, the combination with a stencil-carrying drum, of an ink-container and -distributer within said drum and movable longitudinally thereof, their major axes being arranged transversely of said drum, substantially as set forth. 120

This specification signed and witnessed
this 9th day of February, 1909.
